STATISTICAL MACHINES

Raymond Owen Parmenter, Mitcham, England, assignor to Powers-Samas Accounting Machines Limited, London, England, a British company

Application May 4, 1956, Serial No. 582,762

14 Claims. (Cl. 164—111)

This invention relates to statistical machines and in particular to apparatus for effecting actuation of recording elements, for example punches or set pins for co-operation therewith, arranged in columns each of which consists of a plurality of recording elements supported for movement relative one to another to and from normally inactive positions thereof.

In some forms of statistical machines in which recording elements, as set forth above, are employed, it is possible to effect the simultaneous operation of all the recording elements, but in other machines operation must be effected column by column and heretofore in this last mentioned kind of machine, it has been usual to effect operation of the recording elements by moving a column of operating elements step-wise over each column of recording elements in succession, starting at the first column and finishing at the last. This mode of operation has restricted the rate of operation of the machine because the succeeding operation of the machine cannot be effected until all columns have been traversed by the setting device. It is one object of the present invention to provide a setting apparatus which will reduce the time taken to effect the column-by-column setting of recording elements and so increase the rate of operation of the machine.

In general, this object is achieved by arranging that instead of the recording elements being set by a single stepwise moving setting device, there is provided a plurality of simultaneously operable stepwise moving setting devices arranged to effect parallel setting of portions of the punch unit appropriated thereto.

It is a further object of the invention to provide a setting apparatus which will reduce the number of elements required when setting of recording elements is effected row-by-row as distinct from column-by-column as mentioned above and where in the appended claims reference is made to a line of recording elements the term "line" is deemed to mean either a column or a row of recording elements.

It will be understood that in statistical machines there are employed a variety of forms of apparatus in which elements are arranged in columns and rows each of which consists of a plurality of the elements supported for movement relative one to another to and from normally inactive positions thereof, for example the elements may consist of punches for punching record cards or tape, or set pin elements for co-operation with such punches, or the elements may consist of data-memory elements or of coding or decoding set-bars, and all such elements are deemed herein to be included in the expression "recording elements" where used herein.

According to the present invention there is provided apparatus for use in a statistical machine for effecting actuation of recording elements arranged in lines each of which consists of a plurality of said recording elements supported for movement relative one to another to and from normally inactive positions thereof, said apparatus

2

comprising a push rod for each recording element of a line of recording elements, a swinging support arranged to support said rods for lengthwise movement and for step-wise alignment with successive lines of recording elements, selectively operable operating elements to effect lengthwise movement of the push rods and each connected with one of said push rods and permitting swinging movement of the push rods by the support relative to the operating elements, and means to effect swinging movement of said support.

In order that the invention may be clearly understood one embodiment thereof will now be described, by way of example, with reference to the accompanying drawings in which:

15 Fig. 1 is a side elevation, with parts thereof broken away for clarity, of a portion of apparatus according to the present invention,

Fig. 2 illustrates a part of the driving mechanism for the apparatus shown in Fig. 1, and

20 Fig. 3 is an end elevation, partly in section, looking in the direction of arrow III, Fig. 1.

The apparatus illustrated in the drawings is designed for use with a punch unit for punching statistical record cards but the drawings do not illustrate the whole of a punch unit as punch units having set pins movable lengthwise for the purpose of setting the punch unit are well-known in the art. In Figs. 1 and 3 there are illustrated some of the set pins 1 of a punch unit, the set pins being, as is customary, disposed in columns, one for each column of a card to be punched and are shown in the normally inactive positions thereof from which they are moved lengthwise to effect setting of the punch unit. One column of set pins is shown in Fig. 3 and consists as can be seen from that figure, of twelve set pins 1, one for each data-indicating position of a vertical column of a card. In Fig. 1 there are illustrated only ten of the columns of set pins, the columns being numbered 56 to 65 as it is assumed that the punch unit is one provided for punching 65-column cards. It will, however, be understood that the punch unit could be other than that for a 65-column card, as for example it could be for an 80-column card, for a 40-column card, or for a 36-column card.

45 As will hereafter be described, one embodiment of apparatus according to the present invention is provided with a plurality of set pin actuating units arranged in parallel, of which two are illustrated in Fig. 1, and each of the set pin actuating units is arranged serially to effect

50 setting, column-by-column, of set pins in a plurality of adjoining columns of set pins. In the example herein described, it is assumed that each set pin actuating unit will effect actuation of the set pins in eight adjoining columns of set pins. Thus, if the punch unit is for use

55 with 80 or 40-column cards, there will for such units be provided respectively either ten or five set pin actuating units. In the example illustrated in Fig. 1, where it is assumed that the punch unit is for use with 65-column cards, there will be provided nine set pin actuating units, eight of which units will each be effective to control operation of eight adjoining columns of set pins and the ninth of which will be effective to effect setting of only one column of set pins.

60 Referring to Fig. 1 there is shown, as stated above, two of the nine set pin actuating units, and it is to be understood that the construction of each of the set pin actuating units is similar to that illustrated in Fig. 1 and described below. Each set pin actuating unit includes an actuating member shown in Fig. 1 as a push-rod 2, and the units are supported in parallel spaced relation, as illustrated in Fig. 1, for simultaneous stepwise movement column-by-column over groups of adjoining col-

umns of set pins 1 appropriated thereto, in a manner to be described below. For each actuating member 2 of a unit there is provided a set of selectively operable operating elements to effect serial operation of the actuating members when the members are in operative relation with the set pins of a column appropriated thereto.

The push-rods 2 are supported for lengthwise movement, to and from the inactive position thereof shown in Fig. 1, by a swinging plate 3 pivotally mounted on a fixed stud 4 adjacent the end of the rod 2 remote from the set pins 1. The end of the plate 3 nearest the set pins 1 is connected by shoulder screws 5 to flat bars 6 forming part of driving means common to the plates 3 and operable to swing the plate intermittently about the pivot studs 4 so as to position the push-rods 2 carried thereby successively for co-operation with the columns of set pins 1 to be actuated thereby. As shown in Fig. 1, the group of adjoining columns of set pins 1, numbered from 57 to 64 inclusive, are to be actuated by the rods 2 initially positioned above the column 64, the bars 6 being moved intermittently to the right, as viewed in Fig. 1, so that the rods 2 are successively positioned over the columns 63 to 57. It will be understood from Fig. 1, that with the arrangement shown therein, for a 65-column unit the pin-actuating unit at the extreme left will have imparted thereto the same eight stepwise movements as the adjoining actuating unit, but only on the last of the stepwise movements, when the rods 2 of this unit are disposed above the set pins 1 of column 65, will the rods 2 be effective to actuate set pins.

The rods 2 are supported for lengthwise movement by the lower end 7 of plate 3 and by bearing members 8, 9, carried by the plate. Each rod 2 is provided with a shoulder 10 and a spring 11 extends between the shoulder 10 and bearing 8 to urge the rod 2 to the normally inactive position thereof illustrated in Fig. 1.

The driving means, of which the bars 6 are integers, is illustrated in Fig. 2 from which it will be seen that a bar 6 is engaged by an end of a plunger 12, the bar being retained in engagement with the plunger by a spring 13. The plunger 12 is engaged by a stepped cam 14 secured to a shaft 15 rotatable from the main drive of the machine to which the punch unit is fitted. The cam 14 is shown in the position thereof in which the rods 2 are disposed over the first column of set pins to be operated thereby. Thus considering Fig. 1, and the group of columns of set pins 57 to 64, the rods 2 are disposed for co-operation with the set pins 1 of column 64. As the cam 14 rotates counter-clockwise, as viewed in Fig. 2, the plunger 12 successively co-operates with steps 16, 17, 18, 19, 20, 21 and 22, and as the plunger engages with these successive steps the support plates 3 successively move the columns of rods 2 carried thereby stepwise column by column to the right, as viewed in Fig. 1.

After actuation of the last column of set pins of a group, the cam 14 restores the columns of rods 2 to the initial positions thereof as illustrated in Fig. 1.

Movement of a rod 2 from the normally inactive position thereof shown in Fig. 1 is effected by a normally inactive motion-transmitter comprising a slide 23 supported for lengthwise movement between guide members or comb bars 24. Each slide 23 has an arcuate lower end 25 which is engaged by the upper end of its rod 2 and is provided with a laterally extending pin 26 which is located in a slot 27 in a link 28 pivoted about a fixed pin 29. Movement of the link 28 about its pivot 29 is effected by a transmission rod 30 supported for lengthwise movement by plates 31, 32. Abutting the upper end of each transmission rod 30 is a trigger latching member 33 slidable in guide plates 34 and provided with a shoulder 35 and a spring 36 which extends between the shoulder and one of the plates 34. The spring 36 tends to urge the latching member 33 to the inactive position thereof shown in Fig. 1. The upper end of each trigger latching member is provided with a notch 37 for engage-

ment by a trigger about to be described. The arrangement of the slide 23, link 28, and transmission rod 30 is such that the extent of lengthwise movement of rod 2 is greater than that of transmission rod 30 and, in the apparatus being described, the extent of lengthwise movement of rod 2 is twice that of transmission rod 30.

Movement of the transmission rod 30 is effected by a trigger 38 pivotally mounted on a shoulder screw 39 secured to a trigger support shown as a bar 40. The bar 40 is common to all like triggers 38 to effect operation of like push-rods 2 and, accordingly, there are twelve bars 40 arranged in side-by-side relation, as can be seen from Fig. 3. The triggers are urged by springs 41, to the inactive positions thereof shown in Fig. 1, in which positions they are arrested by stop pins 42 extending laterally from the bar 40. Selection of a trigger to effect operation of its push-rod 2 is effected by a solenoid 43 appropriated thereto, the solenoid being provided with an armature 44 pivoted at 45, Fig. 1, and urged into engagement with the pole face of the solenoid by a leaf spring 46. The armature 44 supports a trigger-setting cam 47 arranged to cooperate with a face 48 of the trigger 38. Thus, if the solenoid 43 is energized, the armature 44 remains in the active position thereof illustrated in Fig. 1 and, on downward movement of the trigger by the bar 40, the trigger-setting cam 47, by engagement with the face 48 of the trigger, causes the trigger to be moved counterclockwise, as viewed in Fig. 1, about its pivot 39 so that the lower end of the trigger 30 will be engaged with the notch 37 of the trigger-latching member 33 and continued downward movement of the trigger by the bar 40 will effect, through member 33, lengthwise downward movement of transmission rod 30 thereby to effect lengthwise movement of its rod 2 which, in turn, effects lengthwise movement of the set pin 1 with which it is aligned. The arrangement is such that, at the instant at which the lower end of the trigger 38 engages the face 48 of the trigger-latching member 33, the continued downward movement of the trigger forcibly pulls the armature 44 away from the pole face of the solenoid 43. Also at about this time the trigger tends to return to the inactive position thereof under the influence of its spring 41, but it is prevented from so doing because it is now engaged in the notch 37 of the trigger latching member 33.

It will be understood that if, during the downward movement of bar 40, the solenoid 43 is not energized then engagement of the face 48 of the trigger with the cam 47 causes the armature 44 to be moved away from the pole face of the solenoid and the spring 41 retains the trigger in the inactive vertical position thereof shown in Fig. 1 so that during the continued downward movement of the bar 40 the trigger is not engaged with its trigger-latching member 33 and accordingly does not effect lengthwise movement thereof.

The bars 40 are supported at their opposite ends by cross shafts 50 of which only one is shown in the drawings, and the cross shafts 50 are carried by eccentric straps 51 connected with eccentrics 52, Figs. 1 and 3, driven by a chain 53 from the main drive of the machine. The cross shafts 50 have their ends supported in blocks 54 slidable vertically in slots 55 formed in frame members 56 thereby, under the action of eccentrics 52 to guide the bars 40 during vertical reciprocation thereof.

In operation of the apparatus the cam 14, Fig. 2, causes the support plates 3 to move the columns of rods 2 carried thereby in succession stepwise over the columns of set pins of the groups thereof to be operated by the rods 2 and signals to effect energization of the solenoids 43 are transmitted in parallel to like columns of groups of solenoids and the signals to the solenoids of a column are transmitted in series to solenoids of the column. Accordingly, it will be understood that for a high speed machine in which signals are derived from a number of different positions for the purpose of producing punched

holes in different fields of a record card, the signals may be transmitted simultaneously to the plurality of set pin-actuating units so that in differing fields of the punch unit columns of set pins therefor can be simultaneously conditioned prior to actuation of the punch unit to effect punching of the card.

In the foregoing description apparatus according to the invention has been described with reference to the use thereof in effecting setting of recording elements column-by-column. It is to be understood, however, that the apparatus may be adapted to effect setting of recording elements row-by-row and that in such case only one actuating unit will be required because twelve is normally the maximum number of rows in which setting is to be effected. Thus when the apparatus is adapted to effect setting row-by-row there will be provided one solenoid 43 for each position in the row in which a setting may be effected and a swinging support similar to a plate 3 is provided to support actuating members each of which is connected to a solenoid 43 appropriated thereto through a connection device such as that obtained by a push rod 2 and arcuate surface 25 and which permits swinging movement of the actuating members relative to the solenoids thereby successively to position the actuating members for cooperation with the successive rows of recording elements. When using this form of the apparatus the solenoids 43 will be actuated by the row-by-row sensing of a record card, for example of a continuously moving card.

It will also be understood that, if desired, the rods 2 may be arranged to cooperate directly with punches thereby to effect punching of a record card. Further, the apparatus may be employed to effect the punching, either directly or through a set bar unit, of a tape fed intermittently by increments equal to the number of columns of a record card from which data is sensed in parallel from adjoining groups of card columns thereby increasing the rate at which data sensed from a record card can be punched, if desired in code, into a tape. Other applications of the apparatus in statistical machines will readily come to the mind of those skilled in the art.

I claim:

1. Apparatus for use in a statistical machine, comprising recording elements arranged in lines each of which consists of a plurality of said recording elements supported for movement relative one to another to and from normally inactive positions thereof, a push rod for each recording element of a line of recording elements, a swinging support arranged to support said rods for lengthwise movement and for stepwise alignment with successive lines of recording elements, and for each push rod a normally inactive motion-transmitter to effect lengthwise movement thereof, a trigger pivoted on a movable trigger support by which the trigger is movable into co-operation with the motion-transmitter to effect operation thereof, said trigger being spring-urged about its pivot to a normally inactive position thereof at which it is prevented from co-operation with its motion-transmitter, a normally de-energized solenoid, an armature for the solenoid normally spring-urged to the active position thereof, and a camming element carried by said armature and co-operating with the trigger thereby on energization of the solenoid to effect movement of the trigger about its pivot to the active position thereof for co-operation with the motion-transmitter.

2. Apparatus according to claim 1, wherein a movable trigger support is provided for all triggers appropriated to like push rods, said trigger supports comprising bars arranged in side-by-side relation, cross shafts providing common supports for said bars, eccentric straps connected with the cross shafts, and rotatable eccentrics co-operating with the eccentric straps to effect movement of the bars and the triggers carried thereby towards and away from said motion transmitter.

3. Apparatus according to claim 2, wherein each mo-

tion-transmitter comprises a slide engaged with the push-rod operable thereby and supported for lengthwise movement, a transmission rod, a trigger latching member co-operating with the transmission rod and engageable by a trigger, and a pivoted link movable about its pivot by the transmission rod and connected with the slide to impart lengthwise movement thereto under control of lengthwise movement of the transmission rod.

4. Apparatus according to claim 3, wherein the trigger-latching member is provided with a notched end for engagement by its trigger when the trigger is in the active position thereof.

5. Apparatus for use in a statistical machine for effecting actuation of recording elements arranged in columns each of which consists of a plurality of said recording elements supported for movement relative one to another to and from normally inactive positions thereof, said apparatus comprising a plurality of plates supported in spaced parallel relation for swinging movement about fixed pivots, a plurality of push-rods, one for each recording element of a column, supported by each said plate for independent lengthwise movement to and from an inactive position thereof, springs to urge the push-rods to the inactive positions thereof, connecting members common to all said plates to effect simultaneous swinging movements thereof, driving means connected with the connecting members to swing said plates about their pivots to effect positioning of the push-rods relative to the columns of recording elements of the groups appropriated thereto, a normally inactive motion-transmitter for each push-rod, a plurality of motion-transmitter operating bars, one for each push rod supported by one of said plates, said bars being arranged in side-by-side relation and supported for common movement towards and away from the motion-transmitters, a plurality of triggers, one for each like push-rod supported by said plates, pivoted on each of said bars and spring-urged to normally inactive positions thereof, a normally de-energized solenoid for each trigger, an armature for each solenoid normally spring-urged to the active position thereof, and a camming element carried by each said armature and co-operating with the trigger appropriated thereto thereby on energization of the solenoid to effect movement of the trigger about its pivot to the active position thereof for co-operation with the motion-transmitter appropriate thereto thereby during movement of said bars to effect operation of the push-rods through the motion transmitters appropriated thereto.

6. Apparatus according to claim 5, wherein each motion-transmitter comprises a slide engaged with the push-rod operable thereby and supported for lengthwise movement, a transmission rod, a trigger-latching member co-operating with the transmission rod and engageable by a trigger, and a pivoted link movable about its pivot by the transmission rod and connected with the slide to impart lengthwise movement thereto under control of lengthwise movement of the transmission rod.

7. Apparatus according to claim 6, wherein the trigger-latching member is provided with a notched end for engagement by its trigger when the trigger is in the active position thereof.

8. Apparatus for use in a statistical machine for effecting actuation of recording elements arranged in columns each of which consists of a plurality of said recording elements supported for movement relative one to another to and from normally inactive positions thereof, said apparatus comprising a plurality of swinging supports arranged in parallel for swinging movement relative to a group of adjoining columns of recording elements appropriated thereto, each said support having mounted thereon a lengthwise movable push rod for each recording element of a column, means to move the supports stepwise simultaneously to align the push rods carried thereby for co-operation with successive columns of recording elements of the groups appropriated thereto,

and for each push rod a normally inactive motion-transmitter, a trigger pivoted on a movable trigger support by which the trigger is moved into co-operation with the motion-transmitter to effect operation thereof, said trigger being spring-urged about its pivot to a normally inactive position thereof at which it is prevented from co-operating with its motion-transmitter, and trigger-setting means including for each trigger a normally de-energised solenoid, an armature for the solenoid normally spring-urged to the active position thereof, and a camming element carried by said armature and co-operating with a trigger appropriated thereto thereby on energisation of the solenoid to effect movement of the trigger about its pivot to an active position thereof for co-operation with the motion-transmitter appropriate thereto.

9. Apparatus according to claim 8, wherein a movable trigger support is provided for all triggers appropriated to like push rods, said trigger supports comprising bars arranged in side-by-side relation, cross shafts providing common supports for said bars, eccentric straps connected with the cross shafts, and rotatable eccentrics co-operating with the eccentric straps to effect movement of the bars and the triggers carried thereby towards and away from said motion transmitter.

10. Apparatus according to claim 9, wherein each motion-transmitter comprises a slide engaged with the push-rod operable thereby and supported for lengthwise movement, a transmission rod, a trigger latching member co-operating with the transmission rod and engageable by a trigger, and a pivoted link movable about its pivot by the transmission rod and connected with the slide to impart lengthwise movement thereto under control of lengthwise movement of the transmission rod.

11. Apparatus according to claim 10, wherein the trigger-latching member is provided with a notched end for engagement by its trigger when the trigger is in the active position thereof.

12. Apparatus for use in a statistical machine, comprising recording elements arranged in columns each consisting of a plurality of recording elements supported for movement relative one to another to and from normally inactive positions thereof, columns of push rods each of which includes a push rod for each recording element of a column thereof, said columns of push rods being 45

each appropriated for co-operation with a group of adjoining columns of recording elements and supported for simultaneous stepwise movement to align the push rods with columns of recording elements in the groups 5 thereof appropriated to the respective columns of push rods, said push rods being also supported for lengthwise movement to effect actuation of recording elements aligned therewith, and selectively operable operating elements, one for each push rod, adapted to effect simultaneous lengthwise movement of push rods in each column thereof thereby to permit simultaneous actuation of recording elements in each of said groups thereof.

13. Apparatus for use in a statistical machine, comprising recording elements arranged in columns each consisting of a plurality of recording elements supported for movement relative one to another to and from normally inactive positions thereof, columns of push rods each of which includes a push rod for each recording element of a column thereof, said columns of push rods being each appropriated for co-operation with a group of adjoining columns of recording elements, a swinging support for each column of push rods, the push rods being supported for independent lengthwise movement relative to the support, spring-urged to inactive positions 20 thereof, and movable with the support stepwise to align the rods with columns of recording elements in the group thereof appropriated thereto, connecting members common to all said swinging plates to effect simultaneous swinging movement thereof, driving means connected 25 with said connecting members to control stepwise swinging movements of the plate, and selectively operable operating elements, one for each push rod, adapted to effect simultaneous lengthwise movement of push rods in each column thereof thereby to permit simultaneous actuation of recording elements in each of said groups thereof.

14. Apparatus according to claim 13, wherein the driving means includes a rotatable stepped cam, and a plunger connecting the cam with said connecting members.
